UNITED STATES PATENT OFFICE

GEORGE B. SCARLETT, OF KENNETT SQUARE, PENNSYLVANIA, ASSIGNOR TO THE GLACIER CORPORATION, OF KENNETT SQUARE, PENNSYLVANIA, A CORPORATION OF DELAWARE

INSULATING WRAPPER

Application filed July 27, 1928. Serial No. 295,816.

The main object of this invention is to provide an insulating and protective wrapper that can be produced at low cost for one time use, that can be packed in flat form to conserve space and for convenience in handling, that does not require great skill in the manipulation and handling thereof to enable the user to properly roll and fold up the wrapper around and enclosing a dry refrigerant unit or units and the article or articles to be carried and refrigerated by such unit or units for a substantial length of time; and that can be utilized to wrap up and enclose containers of ice cream and other chilled or frozen products to form a simple, improved and advantageous carry home package for maintaining such chilled products in an edible condition for several hours.

With the foregoing and other objects in view, the invention consists in certain features, in formation and arrangement and/or in novel combinations, as more fully and particularly described and specified herein-after.

Referring to the accompanying drawings, forming part hereof:—

Fig. 1 shows in top plan an embodiment of the wrapper of my invention, in flat form and top, dotted lines indicating a container and refrigerating units located on the wrapper preparatory to initiating the wrapping operation.

Fig. 2 shows the wrapper of Fig. 1 in edge elevation with certain portions thereof swung up to show the manner of hinging or loosely connecting the same to the main outer wrapper, the article to be wrapped being shown in full lines.

Fig. 3, is a top plan showing the initial step in the wrapping operation, the article to be wrapped and the refrigerating units being indicated by dotted lines.

Fig. 4 is a top plan showing the step in the wrapping operation following that of Fig. 3.

Fig. 5 is a detail section taken in the plane of the line 5—5, Fig. 3.

Fig. 6 is a top plan showing the wrapper when the wrapping operation has been almost completed.

Fig. 7 is a detail section on the line 7—7,

Fig. 4.

Fig. 8 is a perspective showing the completed bundle composed of the container and refrigerating material enclosed within the rolled enclosing wrapper.

Fig. 9 is a detail perspective on an enlarged scale, of portions of the main outside sheet and the thick soft insulating pad or blanket, a corner of one of the facing sheets of said pad being turned up to show the waterproofing and adhesive coating on the inner surface thereof.

The example illustrated of what I now believe to be the preferred mechanical expression or embodiment of the invention, embodies a strong preferably waterproof outside main wrapping sheet 1, of fibrous material such as suitably treated heavy sheet paper, that is elongated both as to length and width; a relatively short and narrow pliable or flexible thick soft or cushioning insulating pad or blanket 2, loosely resting on or contacting the inner surface of the central or intermediate portion of the main outside sheet 1, and movable with respect thereto or separate and disconnected therefrom except as hereinafter pointed out; and a relatively short and narrow interior preferably stiff heavy paper or other fibrous sheet 3, resting on the inner end of the main wrapping sheet and at its inner end secured, at 3^a, to the inner end of the main wrapping sheet, and at its opposite end extending over the pad 2, and intermediate its length, secured in any suitable manner, to the inner end portion of said pad as by staples 3^b, extending transversely through sheet 3, and pad 2.

The main strong outside sheet 1, is of a length to form several overlying spiral convolutions surrounding the article or articles enclosed thereby. This sheet 1, is in width far in excess of the length of the article or articles to be enclosed when arranged transversely thereof and approximately midway between the longitudinal edges of said sheet.

The preferably stiff heavy article-contacting paper or other flexible short narrow inner sheet 3, is at its inner end permanently secured by adhesive or otherwise to the inner

end of the main sheet at 3^a, so as to overlie the same. This inner sheet is preferably at least as wide as the length of the article or articles to be enclosed when arranged transversely thereon, and this inner sheet is preferably long enough to spirally wrap at least once around the articles to be enclosed with the sheet ends overlapping.

This inner sheet 3, is arranged longitudinally and centrally of and on the inner end portion of the main sheet to which it is preferably secured at its inner end only.

The heavy flexible insulating pad 2, is preferably composed of a thick compressible soft mass 2^a, of felted or loosely connected fibres, such as wood fibres, providing a maximum percentage of internal dead air spaces. This thick soft mass 2^a, is covered at its side faces by strong paper sheets 2^b, coated at their inner faces by waterproofing adhesive 2^c, such as bitumen, asphalt or other suitable material, applied in liquid form, whereby these facing sheets are caused to adhere to the fibrous mass 2^a. The pad 2, is in sheet form and as a unitary article consists of the thick soft insulating fibrous mass adhering to and faced at both sides by the sheets 2^b.

This thick insulating pad 2, is arranged longitudinally on the main sheet 1, centrally between the side edges thereof, and is long enough to, preferably, form at least one spiral coil with overlapping ends around the inner sheet 3, enclosing the article to be enclosed. This pad is also longer than the article to be enclosed, preferably, to provide opposite tuck-in side portions to fold up and over to cover and enclose the ends of the article to be enclosed, see Figs. 4, 5, 6, 7 and 8.

The outer portion of the inner sheet 3, Fig. 1, rests centrally and longitudinally on the pad 2, and intermediate its length is permanently secured to the inner end portion of the pad, so that the pad is secured to the inner end of the main sheet 1, through the medium of a flexible neck or hinge formed by the inner end portion of inner sheet 3, while the outer end portion of sheet 3, lies loosely on the pad.

When the wrapper is flattened out, as shown by Fig. 1, the article to be wrapped such as container of ice cream A, is placed transversely on the inner end of the inner sheet 3, with sealed or closed cans or receptacles of chilled or frozen brine or other chemicals or cakes of carbon dioxide ice or other refrigerant unit or units B, at one or both ends of such article A.

The wrapper, starting with its inner end (left hand end, Fig. 1), is then rolled longitudinally toward the opposite end thereof, with the article A, and the refrigerant therein. The wrapper is thus rolled or coiled approximately to the dotted line C, Fig. 1, and the outer free end of inner sheet 3, is picked

up and held to the article overlapping the inner end of said sheet, while the opposite side portions of the main sheet 1, with the pad 2, thereon, are thereupon folded inwardly on the longitudinal fold lines D, Fig. 3 over the central longitudinal portion of the wrapper and the article therein, see Fig. 4, forming the tucked in ends, 6 of the completed bundle, Fig. 8, by completing the rolling or wrapping process as indicated by Fig. 6.

The article and refrigerant, as a unit in the completed bundle, is surrounded circumferentially and at both ends by the insulating pad 2, and the main sheet 1, and in an approximately air tight package that reduces heat exchange to the minimum, and maintains chilled and frozen products in an edible condition for an exceedingly desirable length of time, such as several hours, for carry home purposes. The corners of the inner and outer ends of the main sheet 1, are preferably cut off to provide the tapered ends.

The completely wound wrapper can be secured in any suitable manner or by any suitable means, although I have attained satisfactory results by the use of adhesive. For instance, adhesive can be applied for this purpose, at 3^d, on the outer end of the main sheet 1.

The pad 2, preferably occupies an intermediate portion of the main sheet 1, so that an extended outer end of the main sheet is provided to form an outer layer or layers of the completed package or bundle, Fig. 8, while the inner usually relatively stiff or protective sheet fits tightly around and encloses the container and refrigerant.

The pad 2, is loose and free to render the same self adjusting during the folding operation and to avoid rupture and separation within the fibrous mass thereof by relative longitudinal movements of the facing sheets thereof or for other causes. The fibrous mass of the pad 2 can, for example, be formed of balsam wood, which is fluffed wood fibre, and when found necessary or expedient the invention contemplates and includes the sealing or closing of the edges of the pad to prevent the fibrous mass from fluffing or dusting out from between the sheets 2^b, as for instance by closing the edges of the pad across and between the sheets 2^b by suitable strips of paper, such as a paper of the crinkled, so-called, types.

The disclosure hereof is for illustrative and descriptive purposes, and not for purposes of limiting the scope of the invention except as required by the prior state of the art.

What I claim is:—

1. An insulating wrapper embodying an outer main sheet elongated in length and width, and an inner flexible soft pad that includes a thick fibrous mass layer providing insulation against heat exchange, said pad

coupled to the outer sheet and arranged on the inner side thereof, said wrapper adapted to be rolled up enclosing the article and refrigerant and to be tucked in to cover the ends of the space occupied by the article and refrigerant, with the insulating pad surrounding said space.

5. 2. A wrapper for forming an insulating carry-home package of refrigerated food product, said wrapper embodying an outside main sheet elongated in width and length, and a relatively short flexible thick insulating pad arranged loosely thereon and having flexible hinge connection therewith.

10. 3. A wrapper adapted to be rolled up from flat form with and around the article to be refrigerated and the refrigerant and tucked in to close the ends of the space occupied by said article and refrigerant, to form an insulating refrigerating package; said wrapper embodying an outside main sheet elongated in length and width, and an inside insulating pad including a thick soft fibrous mass covered at both sides by adhering facing sheets.

15. 4. A wrapper adapted to be rolled up from flat form with and around the article to be refrigerated and the refrigerant and tucked in to close the ends of the space occupied by said article and refrigerant, to form an insulating refrigerating package; said wrapper embodying an outside main sheet and an inside insulating pad including a thick soft fibrous mass covered at both sides by adhering facing sheets, said facing sheets having 20 adhering waterproofing coatings on their inner surfaces, said mass embodying loosely meshed or felted vegetable fibres.

25. 5. A wrapper adapted to be rolled up from flat form with and around the article to be refrigerated and the refrigerant and tucked in to close the ends of the space occupied by said article and refrigerant, to form an insulating refrigerating package; said wrapper embodying an outside main sheet elongated 30 in length and width, a relatively short and narrow inner sheet at one end secured to the inner end of the outer sheet and otherwise free therefrom; and a thick flexible insulating pad loosely resting on the outer sheet and at one end portion secured to said inner sheet 35 intermediate the length thereof.

Signed at Kennett Square, county of Chester, Pennsylvania, this 6 day of July, 1928.

GEO. B. SCARLETT.
